UNITED STATES PATENT OFFICE.

ALBERT ULCH, OF CHELSEA, IOWA.

GATE-OPERATING MEANS.

1,148,638.

Specification of Letters Patent. Patented Aug. 3, 1915.

Application filed February 24, 1915. Serial No. 10,289.

To all whom it may concern:

Be it known that I, ALBERT ULCH, a citizen of the United States, residing at Chelsea, in the county of Tama and State of Iowa, have invented certain new and useful Improvements in Gate-Operating Means, of which the following is a specification, reference being had to the accompanying drawings.

This invention relates to new and useful improvements in gate operating means, the main object of the present invention being the provision of an operating mechanism whereby the gate may be readily opened and closed, without the necessity of leaving the vehicle.

Another object of the present invention is the provision of a swinging gate having operating mechanism whereby should the gate be swung too hard, so that in closing the same it would pass beyond the latching point, it can be readily brought back to a closed position with but very little trouble. It will be noted that the gate is provided with double actuating means so that the gate can be swung in opposite directions from either side of the same.

With the above and other objects in view, the invention consists in the novel features of construction, combination and arrangement of parts as will be hereinafter referred to and more particularly pointed out in the specification and claim.

In the accompanying drawing forming a part of this application, Figure 1 is a detail perspective view of a gate constructed in accordance with my invention; Fig. 2 is a side elevation of the same in closed position; Fig. 3 is a detail top plan view illustrating the connecting means which is pivotally mounted upon the gate for operating the latch; Fig. 4 is a detail elevation of the latching mechanism; Fig. 5 is a detail perspective view of the pulley and bracket set cured to the gate, over which the actuating cord is passed; Fig. 6 is a view in perspective illustrating a gate construction in accordance with a further embodiment of my invention; Fig. 7 is a fragmentary elevational view of the latch mechanism comprised in the second form of my gate; Fig. 8 is a fragmentary view in perspective illustrating in detail certain features of the latch construction as disclosed in Figs. 6 and 7, and Fig. 9 is a transverse sectional view taken through the parts illustrated in Fig. 8.

My improved gate, which is generally indicated by the numeral 1, is mounted for swinging movement upon a post 2 and arranged in spaced relation with the post 2 is 60 a second post 3 which is adapted to support the keeper member 4. This keeper member 4 consists of a T-shaped plate, the stem portion of which is provided with an elongated slot 5 adapted to receive a securing bolt 6, 65 whereby this plate may be adjusted vertically with respect to the post 3. The upper portion of the plate 4 is provided with a rounded upper surface having formed therein in spaced notches 7 adapted to receive the 70 movable latch 8 which is carried by the gate 1, whereby to securely retain the gate in its closed position, as illustrated in Fig. 1.

Secured to the upper edge of the gate, at the inner end thereof, is a supporting plate 75 9 and carried thereby is a pivot pin 10 the purpose of which will be hereinafter more fully set forth. In order to actuate the latch 8, to disengage the same from the notches 7 in the plate 4, I provide an actuating member 11 which consists of a pair of rods twisted together to form a loop mounted for pivotal movement upon the pin 10. The rods are then arranged in divergent relation at each end thereof, the inner ends 80 being provided with eyes 12 and secured thereto, are the connecting cords 13. These cords 13 are merged together, as at 14, to form a single strand which is adapted to pass over a pulley 15 supported upon the 85 gate 1 at the outer end thereof and secured to the latch 8, whereby upon a pivotal movement of the member 11 in either direction the latch 8 may be disengaged from the 90 notches 7.

The outer ends of the actuating member 11 are arranged in divergent relation and provided with eyes to which are secured the cords 16 and 17. It will be noted from Fig. 1 that the cords 16 and 17 extend upon 100 opposite sides of the gate and are passed over suitable pulleys 18 and extended down toward the ground so that they may be readily reached from a vehicle or from a person standing on the ground. The lower 105 end of the cords are provided with handle members 19, so that they can be readily grasped when it is desired to actuate the latch 8 and open the gate. The cords 16 and 17, after being secured to the eyes at 110 the outer ends of the rods comprising the actuating member 11, are passed around

suitable pulleys 20 which are supported by brackets 21 so that these cords can be easily actuated. The pulleys 18 are supported by means of brackets 22 mounted upon the 5 upper ends of the posts 23 and mounted upon said posts 23 are the catch members 24 which, when the gate is in its open position, as illustrated by dotted lines in Fig. 1, will engage with the latch 8 and retain the 10 gate in its open position.

From the above description, taken in connection with the accompanying drawing, it will be apparent that a person driving along a road and desiring to open the gate will 15 grasp either one of the handle members 19 according to the direction they are traveling. Upon downward pulling movement of either one of the cords 16 and 17, the actuating member 11 will be moved upon its 20 pivot to release the latch 8 from the keeper 4 so that further pulling movement upon the cords 16 and 17 will tend to swing the gate to its open position, in one direction or the other. Thus, after the person has 25 driven through the open gateway, downward pulling movement upon the opposite cord, on the other side of the gate will release the latch 8 from the catch 24 and permit the gate member to be swung to its 30 closed position, and should the gate member be swung beyond the post 2, it can be readily swung back to its closed position by pulling down upon the opposite cord.

My improved gate, as herein shown and 35 described, is extremely useful on country roads, where fences cross the highway, as this gate can be quickly and readily opened and closed by persons traveling in vehicles.

The device in itself is extremely simple in 40 construction, can be easily operated, and, at the same time, can be manufactured and placed upon the market at comparatively low cost.

In the form of the invention disclosed in 45 Fig. 6, the actuating member 11^a is of substantially the same construction as has been set forth relative to the actuating member 11, and secured to each inner extremity thereof are the cables 16^a and 17^a extending 50 in opposite directions and disposed over the

pulleys 18^a in a manner and for a purpose which is believed to be self-evident. The forward extremities of the actuating member 11^a have secured thereto the flexible member 13^a branching from a single flexible member 25 and secured to the upper end portion of a spring latch 26 carried by the free end of the gate 1^a and adapted to coact with the keeper 27 disposed transversely of the latch post 3^a and provided midway its 60 length with a recess 28 in which the latch 26 is adapted to seat. It is to be observed that the member 25 is disposed through a suitable opening 29 produced in the outer or free end member 30 of the gate 1^a. 65

While I have shown and described the preferred form of my invention, it will be obvious that various changes in the details of construction and in the proportions may be resorted to for successfully carrying my 70 invention into practice without sacrificing any of the novel features or departing from the scope of the invention as defined by the appended claim:

Having thus described this invention, 75 what I desire to claim as new and secure by Letters-Patent is:—

A device of the character described including a swinging gate, an actuating member pivotally supported intermediate its 80 length upon said gate, said member being substantially X-shape, the extremities of the forwardly directed arms being adapted for contact with the opposite sides of the gate and capable of movement independently 85 thereof, means engageable with the rearwardly disposed divergent arms for imparting swinging movement to the member, a latch carried by the gate, and an operative connection between each of the forwardly 90 directed arms and the latch whereby said latch is operated before a forwardly directed arm engages the gate to impart movement to the gate.

In testimony whereof I hereunto affix my 95 signature in the presence of two witnesses.

ALBERT ULCH.
